UNITED STATES PATENT OFFICE

ARTHUR H. ELLIS, OF ROCHESTER, MINNESOTA

ILLUMINATED SIGN

Application filed May 28, 1930. Serial No. 456,658.

The invention relates to a new and improved illuminated sign embodying a shell containing an electric light bulb and disposed in front of a concave reflector, said shell having portions pervious to light and preferably colored, for casting illuminated reflections on said reflector, allowing very pleasing effects to be obtained, primarily for advertising purposes.

10 It is one aim of the invention to provide novel and advantageous means for supporting the bulb socket and the shell and allowing forward and rearward adjustment thereof, such adjustment serving to vary the size 15 of the reflections cast upon the reflector and at the same time changing the proportions of the reflected elements of the reflected sign.

A still further object is to provide a novel construction well adapted for advertising 20 purposes in cigar stores and of such structure as to readily permit the attachment of a cigar lighter at the front end of the shell.

Yet another aim is the provision of unique 25 means for detachably mounting various character-bearing members upon the shell, said members being pervious to light and having their characters in the form of letters, numbers, etc. The provision of these numbers and their attaching means, allows the device 30 to be conditioned for displaying any desired sign upon the reflector.

With the foregoing and minor objects in view, the invention resides in the novel subject matter hereinafter described and 35 claimed, description being accomplished by reference to the accompanying drawings.

Fig. 1 is a vertical sectional view through one form of illuminated sign constructed in accordance with my invention.

40 Fig. 2 is an enlarged vertical sectional view through the bulb-containing shell and associated parts, the bulb and bulb socket being shown in elevation.

Fig. 3 is a vertical transverse sectional view 45 on line 3—3 of Fig. 2.

Fig. 4 is a perspective view of one end of a slot covering strip hereinafter described.

Fig. 5 is a perspective view illustrating two 50 of the character-bearing members and a portion of their attaching means.

Fig. 6 is a perspective view of one of the character-bearing members separated from other parts.

Fig. 7 is a view similar to Fig. 1 but showing a different form of construction.

Fig. 8 is a vertical sectional view through the bulb-containing shell and associated parts, the bulb and socket being in elevation.

Fig. 9 is a vertical transverse sectional view on line 9—9 of Fig. 8.

In the construction herein illustrated, certain specific details have been disclosed and while these details will be rather definitely described, it is to be understood that within the scope of the invention as claimed, variations 65 may be made.

10 denotes a concave reflector which may be mounted in any desired manner, for instance, upon a base 11. The center of the reflector 10 is provided with a rearwardly projecting tubular guide 12 preferably having a set-screw 13. The features of construction so far described, are common to both forms of the invention herein illustrated.

15 In the construction illustrated on Sheet 1 of the drawings, 14 denotes an inherently rigid tube which passes horizontally through the guide 12, the front portion 15 of said tube being bent into U-shape. The front terminal of this tube is suitably secured at 16 to one side of a conventional bulb socket 17, the open end of this socket being presented rearwardly and supporting a bulb 18 in the usual way. The end 19 of the socket which is the end commonly engaged with the conducting wires, is shown as being closed by a plug 20, but when the invention is used for cigar store advertising, this plug may be removed and a conventional cigar or cigarette lighter attached in place thereof.

20 A conical shell 21 contains the bulb 18 and has its smaller end presented toward the reflector, said shell being axially aligned with the straight rear portion of the tube 14. In the present showing, the front end of the shell 21 is formed by an openwork flanged cap 22 which is threaded at 23 upon the bulb socket 17, the flanged edge of said cap being held upon the side wall of the shell 21, by set screws 24. A sheet or sheets of celluloid or

other material pervious to light, covers the openings of the cap 22 and may be of any desired color or colors, one sheet 24' being shown in the drawings.

The peripheral wall of the shell 21 is provided with arcuate circumferentially extending slots 25 and the outer face of said wall is provided with circumferential grooves 26 at opposite edges of said slots. Coiled springs 27 are stretched around the shell 21 and rest within the grooves 26. Between these springs, strips 28 of celluloid or other material pervious to light, extend across the slots 25, the ends of said strips being provided with metal bindings 29 having thin projecting flanges 30 at their ends, said flanges being frictionally held between convolutions of the springs 27. The strips 28 may be colored as desired and they may directly bear characters such as letters, numbers, etc., and by mounting said strips upon the shell in the manner described, it will be obvious that any strip may be quickly and easily detached and another substituted with equal facility.

In the present showing, character-bearing members 31 of sheet form, lie upon the outer sides of the strips 28, being provided with characters 32 which may be cut out, painted or otherwise formed. One end of each member 31 is provided with an outwardly projecting flange 33 whose ends 34 project beyond opposite edges of said member. A plurality of the character-bearing members 31 are disposed upon the strips 28 in overlapped relation as shown in Fig. 3, and the flanged ends 34 are snugly held between convolutions of the springs 27. The members 31 may be of any desired color or colors and they are of course totally or partially pervious to light. By mounting these members in the unique manner shown, the sign may be quickly and easily changed in any required manner.

When the bulb 18 is illuminated, the front end of the shell 21 is similarly illuminated, as is also the periphery of the latter carrying the character-bearing members 31. Consequently, the periphery of the shell and all characters and the like thereon are projected into the reflector 10, giving very pleasing appearance. By loosening the set screw 13 and forwardly or rearwardly adjusting the tube 14, the size of the reflections appearing in the reflector 10 may be changed as desired, moreover, such variations in the size of the reflected sign will be accompanied by a change in the proportions of the reflected elements of the reflected sign while changing its size, thus giving any effect appropriate to the use for which the invention is employed.

In the form of construction illustrated in Figs. 7, 8 and 9, the socket-carrying tube 14' is straight and the socket 17' faces in the opposite direction from socket 17. The shell

21' around the bulb 18', instead of being of slotted construction, is formed from glass or other material previous to light, the smaller end of the shell being threaded upon the socket 17' as denoted at 23'. The large outer end of the shell is closed by a cap 22' having a portion or portions 24'' pervious to light, corresponding to the elements 22 and 24' above described. Character-bearing members 31' of the same construction as the members 31, are secured around the shell 21' by means of coiled springs 27, duplicating the way of securing the members 31 upon the shell 21. The shell 21' may itself be of any desired color or colors and hence, there is no need in this form of construction, of strips such as 28, above described.

Either form of the invention is rather simple and inexpensive, yet will be exceptionally advantageous, primarily for advertising purposes. The various features of construction herein disclosed may be followed if desired, but attention is again invited to the fact that within the scope of the invention as claimed, variations may be made.

What is claimed is:—

1. An illuminated sign comprising a concave reflector having a central guide, an elongated socket support passing through said guide for forward and rearward adjustment, a bulb socket carried by the front end of said socket support, a bulb in said socket, and a shell supported around said bulb, said shell having light-pervious portions for casting illuminated reflections upon said reflector. 100

2. An illuminated sign comprising a concave reflector having a central guide, a rigid tube passing through said guide for forward and rearward adjustment, a bulb socket rigidly supported on the front end of said tube, conductors for said socket passing through said tube, a bulb in said socket, and a shell supported around said bulb, said shell having light-pervious portions for casting illuminated reflections upon said reflector. 110

3. An illuminated sign comprising a concave reflector having a central guide, a rigid tube passing through said guide for forward and rearward adjustment, said tube being curved into U-shape in front of said reflector, a bulb socket having one side secured to the front extremity of said tube, the bulb-receiving end of said socket being disposed toward said reflector, a bulb in said socket, and a conical shell enclosing said bulb, connected with said socket and having its smaller end presented toward said reflector, the larger end and periphery of said shell being pervious to light. 125

4. In an illuminated sign, a concave reflector, a bulb-containing shell pervious to light and mounted in front of said reflector, a plurality of separate character-bearing members pervious to light and adapted to 130

cast reflections on said reflector, said members having thin outwardly projecting flanges, and coiled springs carried by the periphery of said shell, said flanges being frictionally held between convolutions of said springs.

5. In an illuminated sign, a support having a convex portion pervious to light, two spaced coiled springs extending along said convex portion and having closely spaced convolutions, and character-bearing members pervious to light, said members being between said springs and having flanges frictionally held between said convolutions.

10 6. In an illuminated sign, a light-pervious support having a continuous convex periphery provided with two circumferentially extending shallow grooves, two coiled springs snugly surrounding said support and resting in said grooves, and character-bearing members pervious to light, said members being between said springs and having flanges frictionally held between convolutions of said springs.

15 7. In an illuminated sign, a hollow body having a circumferentially extending slot, two coiled springs snugly surrounding said body and extending along opposite edges of said slot, and a covering strip pervious to light, said strip extending over said slot between said springs, said strip having end flanges frictionally held between convolutions of said springs.

20 8. In an illuminated sign, a concave reflector having a central guide, a socket supporting tube passing through said guide for forward and rearward adjustment, said tube being curved and extending to the front of said reflector, a bulb socket having one side secured to the front extremity of said tube, the bulb receiving end of said socket being disposed toward the reflector, a bulb in said socket, and a light-pervious sign mounted in the path on which light rays must travel

25 from said bulb to said reflector.

30 9. In an illuminated sign, a hollow body having a circumferentially extending slot, two coiled springs snugly surrounding said body and extending along opposite edges of said slot, flat character bearing members between the two coiled springs and over said slot, said members having flanges projecting beyond the ends thereof and between the convolutions of the springs.

35 55 10. In a sign, a character-bearing member having a thin lateral flange, the ends of said flange projecting beyond the ends of said member for reception between the convolutions of a spring.

60 60 In testimony whereof I affix my signature.

ARTHUR H. ELLIS.
